PAJAMAS

Clare A. Riepen, Englewood, Colo.

Application June 27, 1941, Serial No. 399,991

2 Claims. (Cl. 2—227)

This invention relates to a pajama pants construction. Pajamas are primarily intended as sleeping garments and any seams in the seat and hip portions become exceedingly annoying especially when the wearers are required to stay in certain fixed positions, such as with invalids and the like.

The principal object of this invention is to entirely eliminate all seams, hems, belts and other structures from the seat and hip portion of the garment so as to provide a smooth, flat contact surface.

Pajamas also tend to become exceedingly uncomfortable in long bed confinements due to the fact that they adhere to the body and will not slide over the bed clothing, thus, pulling tight in certain places and bulging in others. Another object of this invention is to provide a pajama pants so constructed that it will have two layers of fabric over the seat which can freely slide over each other so they will not pull or tighten on the wearer.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a rear perspective view illustrating the seat structure of the improved pajama pants;

Fig. 2 is a vertical sectional view thereof;

Fig. 3 is a detail perspective view illustrating the double seat piece as it appears before being applied to the garment; and

Fig. 4 is a detail cross section through the double seat, taken on the line 4—4, Fig. 1.

The improved pajama pants employ only a front waist band 10 terminating at each side in elastic gussets 11. Neither the gussets 11 nor the waist band 10 extend across the back of the garment. Suitable legs 12 of any desired pattern depend from the band 10 and the gussets 11. The legs are closed along an inner leg seam 16 extending to the crotch of the garment. The back portions of the leg pieces terminate at the crotch level so as not to extend over the seat portion of the garment.

The entire seat portion is formed from a single sheet of fabric which is folded downwardly upon itself at the belt line, as shown in Fig. 3, to form

an inner seat piece 13 and an outer seat piece 14 of similar outline. The adjacent edges of the two pieces 13 and 14 are stitched to the opposite faces of the peripheral edge portions of the leg pieces along a line of stitching, as indicated at 15. The outer seat piece is stitched on the outer face of the garment and the inner face thereof with the garment edge in between the two pieces, as illustrated in Fig. 4.

10 The pieces 13 and 14 extend between the legs 12 to the crotch of the garment to meet the inside leg seams 16. It will be noted that there are no seams of any nature in the back or seat of the pants. It will also be noted that there is 15 no waist band across the back. The entire back is formed by the over-lapped seat pieces 14 and 13 which are free to slide over each other without pulling or bunching the garment.

The garment may be provided with a front 20 opening flap or not as desired. The improved seat structure operates equally well with men's or women's garments.

While a specific form of the improvement has been described and illustrated herein, it is desired to be understood that the same may be varied, within the scope of the appended claims, without departing from the spirit of the invention.

Having thus described the invention, what is 30 claimed and desired secured by Letters Patent is:

1. A pair of pajama pants comprising: a waist band; legs depending from said band, the rear portion of the band and the seat portions of the legs being cut away at the rear of the garment; a seat member extending over the cut away portion of the garment said seat member comprising a sheet of material folded horizontally across its middle to form a downwardly depending inner piece and a downwardly depending outer piece 40 of similar contour and a line of stitching securing the peripheral edge of the back opening of the garment to the adjacent peripheral edges of the two pieces, the inner piece being secured on the inner surface of the garment and the outer piece being secured on the outer surface thereof, the horizontal fold of the sheet being positioned at the waist line of the pants, said two pieces being unattached to each other throughout their areas except along the said peripheral edges 50 thereof.

2. A pair of pajama pants comprising: a waist band; legs depending from said band, the rear portion of the band and the seat portions of the legs being cut away at the rear of the garment; a seat member extending over the cut away por-

tion of the garment said seat member comprising a single piece of material folded horizontally across its middle to form a downwardly depending inner piece and a downwardly depending outer piece of similar contour and a line of stitching securing the peripheral edges of the back opening of the garment to the adjacent periph-

5 eral edges of the two pieces, both of said pieces being pointed at their bottoms and extending into the crotch of the garment to the inner leg seams thereof, the upper edge of the back of the garment being formed by the fold of said piece.
